UNITED STATES PATENT OFFICE

148,517

DESIGN FOR A BIRD FIGURE OR SIMILAR ARTICLE

Charles Brooks, Glendale, Calif.

Application June 6, 1947, Serial No. 139,495

Term of patent 7 years

(Cl. D29—23)

To all whom it may concern:

Be it known that I, Charles Brooks, a citizen of the United States and a resident of the city of Glendale, in the county of Los Angeles and State of California, have invented a new, original, and ornamental Design for a Bird Figure or Similar Article, of which the following is a specification, reference being had to the accompanying drawing, forming part thereof, in which:

Figure 1 is a rear view of the bird figure showing my new design;

Fig. 2 is a perspective view thereof, taken as viewed from the left side; and

Fig. 3 is a view similar to Fig. 2, but viewed from the right side.

I claim:

The ornamental design for a bird figure or similar article, substantially as shown.

CHARLES BROOKS.
